UNITED STATES PATENT OFFICE.

GEORGE BEZANSON, OF WINCHESTER, MASSACHUSETTS, ASSIGNOR TO JULIAN D'ESTE CO., OF BOSTON, MASSACHUSETTS, A CORPORATION OF MAINE.

STEAM TRAP.

Application filed February 21, 1928. Serial No. 256,048.

This invention relates to an improved steam trap which may be utilized for returning the condensed steam of a steam heating system to the boiler. It also may be employed for forcing water supplied thereto from any source into a boiler or into a container positioned either above, or below the trap, or to any discharge pipe for conveying the water to any desired location.

10 The object of the invention is to provide a steam trap of the character set forth, which is simple and efficient in its operation and has very few moving parts which cause friction to interfere with the easy operation of the 15 float which is provided in the trap such as tight fitting steam pistons, or packed trunnions and packed joints.

One of the novel features of the invention consists in a valve for supplying steam to the 20 steam trap and a valve for allowing steam or air to pass out of the steam trap, both of the valves being operated by fluid under pressure, such as water from the city main, said fluid being admitted to the steam and air valves 25 simultaneously, or cut off therefrom by a valve which is operated by the float.

The invention further consists in certain 30 details of construction whereby the efficient and easy operation of the apparatus is insured.

The invention finally consists in the combination and arrangement of parts set forth in the following specification and particularly 35 pointed out in the claims thereof.

Referring to the drawings:

Figure 1 is a vertical sectional elevation of my improved steam trap.

Fig. 2 is a side elevation as viewed from the left of Fig. 1.

Fig. 3 is a sectional elevation taken on line 3—3 of Fig. 2 viewed in the direction of the arrows thereon.

Fig. 4 is a sectional elevation taken on line 4—4 of Fig. 1 illustrating the rock shaft for the float and the parts operating in connection therewith.

Fig. 5 is a sectional elevation of the air valve.

Like numerals refer to like parts throughout the several views of the drawings.

In the drawings, 10 is a steam trap, 11 the casing thereof, 12 a chamber contained within the casing, and 13 is a head fastened by screws 14 to the body portion of the casing. 15 is the steam valve consisting of a body portion 16 having an inner chamber 17 and an outer chamber 18 with a valve seat 19 interposed therebetween in contact with which a valve member 20 is held by means of a spring 21, one end of which bears against the valve member 20, the other end of which bears against a cap 22 having screw-threaded connection at 23 with the body portion 16. The valve member 20 is connected by a valve stem 24 to a diaphragm 25 which is clamped to a standard 26 by a cap 27 and bolts 28.

Steam enters the outer chamber 18 of the steam valve 15 through a pipe 29 and passes from said outer chamber 18 to the inner chamber 17, and thence through a pipe 30 into a 70 passage 31 which extends through the cap 13 forming a portion of the casing 11 into the upper portion of said casing, the passage emerging into the chamber 12 at the top thereof. A baffle 32 projecting downwardly 75 from the top of the casing in alignment with the outlet end of the passage 31 directs the steam downwardly in the chamber 12 when it emerges from the passage 31. The valve stem 24 is slidably mounted in a bushing 80 33 which has screw-threaded engagement with a sleeve 34, the sleeve 34 having screw-threaded engagement with the bottom 35 of the standard 26 and being locked thereto by a lock nut 36. A vent valve 37 illustrated 85 in detail in Fig. 5 consists of a body portion 38 and a cap 39. A diaphragm 40 is clamped between the body portion 38 and the cap 39 and has fastened to it a needle member 41, the pointed end 42 of which enters a port 43 in the 90 body portion of the valve. Normally the pointed end of the needle valve is held out of engagement with the seat 44 of the valve by a spring 45 which encircles the needle member and bears at one end against the body portion 38 and at the other end against a washer 46, which bears against the diaphragm 40.

Steam and air enter the valve through a 95 passage 47, and pass out of the same through 100

a passage 48 and pipe 49 to the atmosphere. It will thus be seen that the steam valve is closed by the spring 21 and that the vent valve is opened by the spring 45. The stem 50 of the vent valve has screw-threaded connection with the body portion 16 of the steam valve, and the passage 47 opens into the inner chamber 17 of the steam valve which is connected to the pipe 30 which opens into 10 the passage 31, and thus connects the inner chamber 17 and the vent valve passage 47 with the chamber 12 of the trap casing.

The vent valve 41 is closed and the steam valve is opened by fluid, such as water, under 15 pressure and this fluid is simultaneously admitted to both of the valves. The steam valve 15 has a pipe 51 opening into a chamber 52 within the cap 27 and this pipe 51 is connected to a valve 53 by connections 54 and 55, a T 20 56 and other connections 57 and 58. The T 56 is connected by a nipple 59 to the vent valve cap 39 and opens into a chamber 60 on the opposite side of the diaphragm 40 from that where the spring 45 is located in said 25 vent valve.

The valve 53 consists of a body portion 62 having water passages 63 and 64 out of alignment with each other, and between these passages is interposed a slide valve 65 which is 30 slidably mounted in the body portion 62 and has a port 66 therein. The slide valve has a stem 67 provided with an extension 68, the extension 68 having a slot 69 therein into which a pin 70 projects. The pin 70 is fast 35 to an arm 71 and projects laterally therefrom into the slot 69. An arm 83 is mounted upon a rock shaft 72 and is prevented from rocking on said shaft by a squared portion 73 of the shaft which projects through the 40 hub 74 of said rocker arm 83. The rock shaft 72 has a bearing at one end in a bushing 75 which has screw-threaded engagement with one side 76 of the casing 11 of the trap. In this bushing there is a spring 77 provided, one 45 end of which bears against one end of the shaft 72, the other end of which bears against the closed end 78 of the bushing 75.

The opposite end of the rock shaft 72 is supported in a bearing 79 which constitutes a 50 bushing and has screw-threaded engagement with the side 80 of the casing 11. The rock shaft 72 is provided with a shoulder 81 which bears against a washer 82 of composition material of soft metal and is held there- 55 against by the action of the spring 77 which forces the rock shaft toward the right, Fig. 4, thus bringing the shoulder 81 against the soft metal washer 82, which is positioned in a chamber 83' provided in the bearing 79. 60 The washer 82 is held in position within the bearing also by a sleeve 84 which has screw-threaded engagement with the bearing 79. To the extreme outer end of the rock shaft 72 there is fastened the arm 71 which is 65 clamped to the rock shaft by a nut 86 having

screw-threaded engagement with the rock shaft 72.

A screw 87 in the extension 68 of the valve stem 67 limits the distance to which the pin 70 can move upwardly in the slot 69. A float 70 88 is fast to the arm 83 within the casing 11. The arm 83, shaft 72, arm 71 and pin 70 constitute, as a whole, a rocker member. Water under pressure from the city main enters the valve 61 through a pipe 89 in alignment with 75 the passage 63. The casing 11 of the trap is provided with an inlet orifice 90 and with a discharge pipe 91.

The general operation of the invention hereinbefore specifically described is as follows:— 80 Water condensation or water from any source enters the chamber 12 of the casing 11 at the inlet orifice 90. As the water accumulates in the casing 11, the float 88 moves upwardly. This causes the rock shaft 72 to be rocked 85 through the arm 83 and the rocking of the rock shaft 72 causes the arm 71 to be rocked downwardly, thus moving the pin 70 downwardly along the slot 69 until it arrives at the bottom of said slot, whereupon the valve 90 stem extension 68 and the valve stem 67 will be moved downwardly, causing the port 66 of the valve 65 to be brought into alignment with the passage 63 as well as the passage 64, and the water entering under pressure 95 through the pipe 89 will then pass through the valve 53 and through the connections 58, 57, T 56 and connections 55, 54 and 51 into the chamber 52 of the steam valve, and there pressing against the diaphragm 25, will push 100 the valve stem 24 and valve member 20 downwardly, opening the passage 92 between the outer chamber 18 and the inner chamber 17 of the steam valve and allow the steam to pass through the pipe 29, through the chamber 18 105 and chamber 17 and pipe 30 and through the passage 31 into the chamber 12 of the trap casing. At the same time water will pass from the T 56 through the nipple 59 into the chamber 46 in the vent valve 37 and pressing 110 against the diaphragm 40 will cause the member 41 to close the port 43, thus the vent valve 115 will be closed and the steam valve will be opened so that passage of steam and air from the casing 11 through the passage 31 and outwardly through the vent valve by way of the outlet passage 48 therein will be stopped and steam will be admitted as before described through the same passage 31 and into the chamber 12 of the casing. This operation 120 of the steam trap occurs when the float 88 has arrived at a predetermined position in its upward movement, the steam entering the casing 11 as hereinbefore described, and the vent valve then being closed, the water which is in the casing 11 will pass outwardly through the pipe 91 to a boiler, to which the pipe 91 is connected, it being understood that the trap will be positioned above the boiler in 125 this case. 130

When the float has descended to nearly its lowermost position as the water passes out of the casing 11, the pin 70 will engage the screw 87 in the extension 68 and move the valve stem 5 67 upwardly, together with the port 66 therein to the position illustrated in Fig. 1, thus closing the passage 63 against further admission of water under pressure and the spring 21 will then operate to close the steam valve, 10 and the spring 45 will simultaneously operate to open the vent valve, thus the steam valve is closed and the vent valve opened so that the operation hereinbefore set forth may be repeated.

15 The shaft 72 and its bearings are to be made the subject-matter of another application.

I claim:

1. A steam trap having, in combination, a casing provided with an inlet orifice and a 20 discharge orifice, a steam valve connected by a passage into said casing, a vent valve connected to said passage through said steam valve, said steam and vent valves operable independently of each other, connections from 25 said steam and vent valves to a source of fluid under pressure, a float in said chamber, and means operated by said float to alternately admit said fluid to and shut off said fluid from said valves.

30 2. A steam trap having, in combination, a casing provided with an inlet orifice and a discharge orifice, a steam valve connected by a passage into said casing, a vent valve connected to said passage through said steam 35 valve, said steam and vent valves operable independently of each other, connections from said steam and vent valves to a source of fluid under pressure, a float in said chamber, and means operated by said float to simultaneously admit said fluid to said valves.

35 3. A steam trap having, in combination, a casing provided with an inlet orifice and a discharge orifice, a steam valve connected by a passage into said casing, a spring operating 45 to close said steam valve, a vent valve connected by a passage into said casing, a spring operating to open said vent valve, connections from said steam and vent valves to a source of fluid under pressure said steam and vent 50 valves operable independently of each other, a float in said casing, and means operated by said float to simultaneously admit said fluid under pressure to said valves to open said steam valve and close said vent valve.

55 4. A steam trap having, in combination, a casing provided with an inlet orifice and a discharge orifice, a steam valve connected by a passage into said casing, a spring operating 60 to close said steam valve, a vent valve connected by a passage into said casing, a spring operating to open said vent valve, connections from said steam and vent valves to a source of fluid under pressure, said steam and vent valves operable independently of 65 each other, a float in said casing, and means

operated by said float to simultaneously shut off said fluid under pressure from said valves and allow said steam valve to be closed by its spring and said vent valve to be opened by its spring.

5. A steam trap having, in combination, a casing provided with an inlet orifice and a discharge orifice, a vent valve and a steam valve connected by a passage into said casing, connections from said vent valve to a source 70 of fluid under pressure, and connections from said steam valve to a source of fluid under pressure, said steam and vent valves operable independently of each other, a shut-off member in said connections, a float in said casing, so and means connecting said float to said shut-off member whereby said fluid may be admitted to said valves to operate the same.

6. A steam trap having, in combination, a casing provided with an inlet orifice and a 85 discharge orifice, a vent valve and a steam valve connected by a passage into said casing, connections from said valves to a source of fluid under pressure, a slide valve in said connections, a stem on said slide valve provided 90 with a slot, a float in said casing, a rocker member to which said float is fastened, and a pin on said rocker member projecting into said slot, whereby a reciprocatory motion may be directly imparted to said slide 95 valve by said rocker member at the end of each movement in opposite directions respectively of the rocker member, whereby said fluid may be admitted to said valves to operate the same simultaneously, and may be 100 shut off from said valves simultaneously.

7. A steam trap having, in combination, a casing provided with an inlet orifice and a discharge orifice, a vent valve connected by a passage into said casing, said vent valve embodying 105 a diaphragm, a needle member fast thereto, and a spring acting normally to hold said valve open, connections from said vent valve to a source of fluid under pressure, a slide valve in said connections, a float in said casing, and a rocker member directly connecting said float to said slide valve, whereby said fluid may be admitted to the vent valve to close the same.

8. A steam trap having, in combination, a 115 casing provided with an inlet orifice and a discharge orifice, a steam valve connected to a passage provided in the walls of said casing and leading into the upper portion of said casing, a vent valve connected to said steam valve on its inner end portion, connections from said steam valve and said vent valve to a source of fluid under pressure, a slide valve positioned in said connections, a float in said casing, and a rocker member directly connecting said float to said slide valve, whereby said fluid may be admitted to the steam valve and to the vent valve to operate the same.

9. A steam trap having, in combination, a casing provided with an inlet orifice and a dis-

- charge orifice, a steam valve connected by a passage into said casing, connections from said steam valve to a source of fluid under pressure, a slide valve positioned in said connections, a float in said casing, and a rocker member directly connecting said float to said slide valve whereby said fluid may be admitted to the steam valve to operate the same, said means embodying a rock shaft, an arm 10 fixed thereto inside said casing to which said float is connected, another arm fast thereto outside said casing, and means directly connecting said last-named arm to said slide valve, a shoulder on said rock shaft, a bearing 15 in which said shaft is loosely mounted, a washer on said shaft between the shoulder and bearing, and a spring acting to press said shoulder against said washer.
10. A steam trap having, in combination, 20 a casing provided with an inlet orifice and a discharge orifice, a vent valve connected by a passage into said casing, connections from said vent valve to a source of fluid under pressure, said connections embodying therein two fluid passages oppositely disposed to each other, a slide valve provided with a port positioned in said connections and slidable transversely of and between said passages, a float in said casing, and a rocker member 25 directly connecting said float to said slide valve whereby said fluid may be admitted to said vent valve to close the same, said rocker member embodying a rock shaft loosely mounted in bearings in said casing, said rock shaft being provided with a shoulder, one end of the bore of one of said bearing members being closed, a washer of composition material positioned in a chamber provided in the other bearing member and bearing 30 against an end wall thereof, and yielding means to force said shoulder against said washer.
11. A steam trap having, in combination, 35 a casing provided with an inlet orifice and a discharge orifice, a vent valve connected by a passage into said casing, connections from said vent valve to a source of fluid under pressure, said connections embodying therein two fluid passages oppositely disposed to each other, a slide valve provided with a port positioned in said connections and slidable transversely of and between said passages, a float in said casing, and a rocker member 40 directly connecting said float to said slide valve whereby said fluid may be admitted to said vent valve to close the same, said rocker member embodying a rock shaft loosely mounted in bearings in said casing, said rock shaft being provided with a shoulder, one end of the bore of one of said bearing members being closed, a washer positioned in a chamber provided in the other bearing member and bearing against an end wall thereof, and means to force said shoulder against said washer.
12. A steam trap having, in combination, 45 a casing provided with an inlet orifice and a discharge orifice, a vent valve connected by a passage into said casing, connections from said vent valve to a source of fluid under pressure, said connections embodying therein two fluid passages oppositely disposed to each other, a slide valve provided with a port positioned in said connections and slidable transversely of and between said passages, a float in said casing, and a rocker member 50 directly connecting said float to said slide valve whereby said fluid may be admitted to said vent valve to close the same, said rocker member embodying a rock shaft loosely mounted in bearings in said casing, said rock shaft being provided with a shoulder, one end of the bore of one of said bearing members being closed, a washer positioned in a chamber provided in the other bearing member and bearing against an end wall thereof, and means to force said shoulder against said washer.
13. A steam trap having, in combination, 55 a casing provided with an inlet orifice and a discharge orifice, a vent valve connected by a passage into said casing, connections from said vent valve to a source of fluid under pressure, said connections embodying therein two fluid passages oppositely disposed to each other, a slide valve provided with a port positioned in said connections and slidable transversely of and between said passages, a float in said casing, and a rocker member 60 directly connecting said float to said slide valve whereby said fluid may be admitted to said vent valve or shut off therefrom, said rocker member embodying a rock shaft loosely mounted on bearing members in said casing spaced apart, one of said bearing members being provided with a chamber into one end of which said shaft projects, the other end of said chamber being closed, the other of said bearing members having a port 65 therein to receive said shaft, and a second chamber adjacent the inner end of said port, a washer in said second chamber through which the shaft projects, and a spring in said first-named chamber bearing against said shaft and forcing the shoulder thereon against said washer.
14. A steam trap having, in combination, 70 a casing provided with an inlet orifice and a discharge orifice, a vent valve connected by a passage into said casing, connections from said vent valve to a source of fluid under pressure, said connections embodying therein two fluid passages oppositely disposed to each other, a slide valve provided with a port positioned in said connections and slidable transversely of and between said passages, a float in said casing, a rocker member 75 directly connecting said float to said slide valve whereby said fluid may be admitted to said vent valve or shut off therefrom, said

rocker member embodying a rock shaft loosely mounted on bearing members in said casing, spaced apart one of said bearing members being provided with a chamber into 5 one end of which said shaft projects, the other end of said chamber being closed, the other of said bearing members having a port therein to receive said shaft, and a second chamber adjacent the inner end of said port, a 10 washer in said second chamber through which the shaft projects and a spring in said first-named chamber bearing against said shaft and forcing the shoulder thereon against said washer, and a sleeve having 15 screw-threaded engagement with the side wall of said second chamber and bearing against said washer, whereby the washer may be forced against the end wall of the second chamber.

20 In testimony whereof I have hereunto set my hand.

GEORGE BEZANSON.
